UNITED STATES PATENT OFFICE.

CHARLES E. HEYER, OF CHICAGO, ILLINOIS, ASSIGNOR TO ARTHUR M. BARNHART, ALSON E. BARNHART, AND CHARLES E. SPINDLER, OF SAME PLACE.

DESIGN FOR A FONT OF PRINTING-TYPE.

SPECIFICATION forming part of Design No. 13,560, dated January 30, 1883.

Application filed November 22, 1882. Term of patent 14 years.

To all whom it may concern:

Be it known that I, CHARLES E. HEYER, a citizen of the United States, residing in the city of Chicago, county of Cook, and State of Illinois, have invented and produced a new and original Design for a Font of Printing-Types, of which the following is a specification, reference being had to the accompanying illustration, forming a part hereof.

10 The character of the design is a script letter having a back slope; and it consists of capitals, lower-case, figures, and points.

15 A special feature of the design is the back-sloping of the letter, consisting of a hair-line, excepting on the bottom of the letter, where it forms a rounded heavy swell on the bottom line of the letter. On the top of capitals A C D E F G H K L N O P Q T W X Y Z, lower-case

c e m o r s t z th, and figures 1 2 3 5 7 8 0 is also a light swell or filling in. Through the center of capitals C, G, and O runs a hair-line in a diagonal direction downward to the descending line of the letter. The cross-line in the center of capitals F H X and lower-case t and th forms a swell drop hair-line tapering to one end of it.

I claim—

The design for a font of printing-types, the style being a back-slope script with the marked contrast between the hair-line top and the heavy swell bottom, combined as described and shown in the accompanying illustration.

CHARLES E. HEYER.
